DESIGN FOR A COMBINATION ELECTRIC HEATER AND AIR COOLING CABINET

William E. Cranston, Jr., Los Angeles, Calif., as-
signor to Thermador Electrical Manufacturing Co., Los Angeles, Calif., a corporation of
California

Application February 23, 1937, Serial No. 67,805

Term of patent 7 years

To all whom it may concern:

Be it known that I, William E. Cranston, Jr., a citizen of the United States, residing at Los Angeles, in the county of Los Angeles and State of California, have invented a new, original, and ornamental Design for a Combination Electric Heater and Air Cooling Cabinet, of which the following is a specification, reference being had to the accompanying drawing, forming part thereof.

Fig. 1 is a front elevational view of a combination electric heater and air cooling cabinet embodying my new design;

Fig. 2 is a side view; and

Fig. 3 is a top plan view thereof.

I claim:

The ornamental design for a combination electric heater and air cooling cabinet, as shown.
